UNITED STATES PATENT OFFICE

ARTHUR O. AUSTIN, OF NEAR BARBERTON, OHIO, ASSIGNOR, BY MESNE ASSIGNMENTS, TO THE OHIO BRASS COMPANY, OF MANSFIELD, OHIO, A CORPORATION OF NEW JERSEY

HEATER FOR INSULATORS

Application filed December 16, 1929. Serial No. 414,349.

This invention relates to heating means for insulators, and has for one of its objects the provision of a heating device which will prevent the accumulation of moisture or other 5 conducting substance on the surface of the insulator tending to reduce the insulation afforded thereby.

A further object of the invention is to provide heating means which shall be of improved construction and operation and which 10 will reduce the insulating properties of the insulator but little, if any.

Other objects and advantages will appear from the following description.

15 The invention is exemplified in the combination and arrangement of parts shown in the accompanying drawings and described in the following specification, and it is more particularly pointed out in the appended 20 claims.

In the drawings:

Fig. 1 is a somewhat diagrammatic elevation with parts in section showing one embodiment of the present invention.

25 Fig. 2 is a view similar to Fig. 1 showing a slightly different arrangement of the invention.

Fig. 3 is an elevation with parts in section showing another form of the invention.

30 Fig. 4 is an elevation showing still another modification.

In transmission lines operating at high voltage, considerable difficulty is caused by heavy leakage currents to ground or by insulators arcing over where the insulators are subjected to fog or to chemical or dust deposits. Lines operating along the sea coast or along lakes where salt or other chemical deposits become heavy, are likely to arc over, 35 particularly when the insulators are subjected to fog or rain. In the vicinity of railroads, cement plants, coke ovens or other locations where there are discharges into the air, conditions are likely to be very severe. Along 40 railroad lines, insulators coated with a de-

posit are likely to be subjected to heavy discharges of steam from the locomotive which greatly increases the leakage, and sometimes causes an arc to ground interrupting the service. On many lines, the discharges on 50 the insulator, frequently cause radio disturbances.

The above considerations apply not only to transmission insulators of either the suspension, strain or pin type, but also to bushings, bus insulators and other insulating supports; both on the line and at stations. Due to the presence of spray ponds, very severe 55 conditions frequently exist at the electrical station. In many cases, the outer ends of bushings projecting from station walls or roofs have to be increased in size in order to prevent arcing under the more severe 60 conditions existing in fog or rains.

It is well recognized that if the surface 65 of the insulator can be maintained in a dry condition the danger of arcing is greatly reduced or eliminated. Where the surface of the insulator can be maintained in a dry condition, heavy deposits do not cause trouble to 70 the same extent as where they are damp or wet. Where the surface is maintained in a dry condition, the deposits apparently do not adhere so strongly to the surface, consequently, wind or wind and rain tend to keep the 75 surfaces cleaner than where the surfaces are wet for a great portion of the time. This is probably due, in part at least, to the fact that the leakage current or charging current flowing over the surface of the insulator is greatly 80 reduced where the surface is kept dry. This leakage or charging current flowing over the surface undoubtedly forms new compounds with the deposit in many cases, producing deposits which are highly conducting 85 when damp or wet.

While it is recognized that maintaining the temperature of the insulator above the dew point will greatly improve the effective insulation of the insulator and reduce the dan- 90

ger of arcing to ground for a given electrical stress, it has been found difficult and expensive to warm the insulator, particularly where the line voltage is high, without lowering its effective insulation for lightning or other severe conditions.

In the present invention, an arrangement is employed which makes it possible to provide an insulator of high length efficiency or 10 arcing voltage for abnormal conditions so that high electrical integrity may be maintained for these conditions, and, at the same time, permits of heating of the insulator to raise at least an appreciable portion above the 15 condensation point.

In the scheme used, it is possible to apply the improvement to a part or all of the insulator as desired. In many cases, a part of the insulator only need be equipped with heating 20 means. This reduces the cost and makes it possible to use ordinary insulating elements for the remainder of the insulator. Keeping the insulator surface dry, even though it may be covered by a deposit, makes it possible to 25 provide high effective flashover voltage for very severe conditions, such as lightning, where the surface deposits do not necessarily affect the performance of the insulator to the same degree as fog or damp surface under 30 the normal operating voltage. This applies to suspension or dead end strings, bushing insulators, tandem insulators or other types of insulation.

The difficulties of providing satisfactory 35 means for raising the temperature of the working surfaces of insulators has heretofore prevented the use of such means for high voltage transmission lines. The present invention, however, makes it possible to provide 40 insulators with heating means which may be readily constructed and applied to any transmission line, particularly those where it is desirable to maintain a high standard of insulation even under the most severe conditions. A part or all of the insulator string 45 may be heated as desired. In general, a part of the insulator string only need be heated. When fogs occur which are most likely to cause flashover, the transients or abnormal 50 voltage disturbances usually have a comparatively small magnitude compared to those during electrical storms. If, therefore, a portion of the insulator is given a high effective resistance for fog conditions or when rain 55 first starts to fall, it is possible that a portion of the insulator string only need be provided with heating means.

Fig. 1 shows an insulator composed of two parts, the upper part having a heated shell 60 10, and the lower part composed of suspension insulator elements 11 of any suitable type. The insulating shell 10 is provided with flanges 12 and a safety or supplemental core 13. The space between the shell and 65 the core 13 is filled with an oil or insulating

medium 14. The shell 10 is provided with an attachment 15 for attaching to the tower. A tubular member 16 is placed inside of the shell or provided in the core 13. The lower end of this member is open at 17 and the upper end 18 is attached to a flexible tubular member 19. The cap 20 is provided with an outlet 21 which is attached to a flexible tube 22, communicating with an expansion chamber or reservoir 23. The chamber 23 is connected by pipe 24 to the lower end of a heated tubular member 25. The tubular member 25 is heated by a resistance element 26 which may be placed either inside or outside of the member 25. In operation, the terminals 27 and 28 of the heating element 26 are connected to a suitable source of energy. This in general will consist of an auxiliary line 31, Fig. 2, running along the transmission line but operating at a relatively low voltage. This line may be energized from any suitable means such as an electrostatic coupling 32 with a step-down transformer 33, as shown in Fig. 2, or by any suitable step-down transformer. In operation, the insulating fluid 14 which may be oil or even air in some cases is heated. Where the column 25 is of sufficient length, the fluid in the column will be lighter than in the column 24 and cause the fluid to flow into the tube 16 and out the lower end at 17. Suitable venting means is provided between the circulating tubes so that where oil or a fluid of this type is used, air may escape into the expansion chamber through a small vent by a small tube or trap 29. This prevents the system from becoming airbound.

It is evident that with this arrangement, the fluid is caused to heat a large portion of the insulating shell. It of course is possible to reverse the circulation as shown in Fig. 2, allowing the heated fluid from the tube 30 to enter at the top of the insulator and removing the colder fluid from the interior of the insulator at the bottom until the whole is warmed sufficiently. It is also evident that with a system of this kind, electrical heating is not essential, but that the heating means may be provided by gas, oil, or any suitable means. Since the heating is applied from a separate circuit, it may be controlled by a remote control system by manual operation or by automatic appliances, if desired. The heating need be applied only during conditions when flashover is likely to take place unless the insulator is warm.

In radio tower installations or in some stations, it is possible to supply the heated fluid or air by a forced circulating system. For this a pump or blower 35 is placed in the system. This may be driven by any suitable means and any number of insulators supplied from the heating fluid. In general, the tubes leading to and from the insulators 125 130

should be of poor heating conductivity or insulated to prevent radiation. Where air is used for heating the insulators, it is usually not necessary to provide a return tube or conduit. In order to provide necessary movement in the insulator, the ducts or tubes connected to the insulator should be of flexible construction. Any suitable type of hose, either metal fabric or rubber, may be used, 10 depending upon the conditions. If desired, ball and socket fittings or those of a corrugated or diaphragm type may be provided. Where the motion of the insulator is restricted by the use of trunnions or hinge connection, the inlet and outlet members may be incorporated with these members. Where the insulators are rigid as in bus and switch construction, the matter of connection is 15 very simple. The expansion chamber 23 provides a reservoir so that slight leakage will not interfere with the operation of the insulator. Since the temperature of the circulating or heating fluid will be an approximate indication of the condition of the 20 insulator, the temperature of this fluid may be made to control an automatic thermostat for regulating the heating means.

It may sometimes be found desirable to provide a heating duct or conduit in the material of the insulator itself. Such an arrangement is shown in Fig. 3 in which a helical duct 36 is formed in the porcelain of the dielectric member 10 and communicates at one end with a pipe or tube 37, by which a 25 heating medium may be supplied to the duct 36. After circulating through the duct 36, the heating medium may discharge through an opening 37 into the interior of the tubular member 10, and if the medium be air, it may be permitted to escape through a vent 38 at the top of the insulator. If the medium be liquid, it may be returned through a return tube communicating with the top of the insulator. It of course is not essential where air 30 is used that it be returned through the center of the insulator but it may be permitted to escape at the lower end through a suitable vent. However, if it is returned through the center of the insulator, it will have additional opportunity for heating the shell. The 35 heating medium may be supplied by a suitable pump or blower situated at any convenient position, and the same source of supply may be used for any number of insulators distributed along the line.

In some cases it may not be desirable to have a mechanical connection of any kind with the insulator or to provide a special form of insulator through which the heat 40 medium may be circulated. One means for heating the insulators under such conditions is shown in Fig. 4, in which a radiator 39 is provided with a suitable reflector to direct the heat against the insulator string 40. The 45 radiator 39 may be supplied with an electrical

heat element or any other suitable means for radiating heat, and the reflector is so constructed and shaped as to concentrate the heat upon the dielectric members. The current for the radiator 39 may be supplied 50 from any suitable source, such as that described in connection with Fig. 2, or from a separate conductor or conductors for supplying current to the radiator. It is, of course, apparent that any number of radiators 55 may be supplied from the same source and that the supply may be controlled from a station at a distance from the towers so that it will not be necessary to heat the insulators except when the weather conditions require. This same thing is true, of course, in connection with Fig. 3 in which the heat medium may be shut off when it is not required.

I claim:

1. The combination with an insulator, of a circulating medium disposed in contact with a portion of said insulator, and means for heating said medium. 60
2. The combination with an insulator, of a circulating medium for heating said insulator, and means disposed at a distance from said insulator for heating said medium. 65
3. The combination with an insulator having a chamber therein, a conduit connected with said chamber, and means for supplying a heating medium through said conduit to said chamber. 70
4. The combination with an insulator having a chamber therein, a conduit connected with said chamber, a circulating medium disposed in said chamber and conduit, and means connected with said conduit away from said insulator for heating said medium. 75
5. The combination with an insulator having a chamber therein, of a circulating medium disposed in said chamber, and means for heating a restricted portion of said medium to cause heat to be carried to said insulator by the circulation of said medium. 80
6. The combination with an insulator having a chamber therein, of a flexible conduit disposed outside of said insulator and connected with said chamber, and means for supplying a heated medium through said conduit to said chamber. 85
7. The combination with an insulator having a chamber therein, of a conduit having opposite ends thereof communicating with said chamber, and means for heating a circulating medium in said chamber and conduit and for causing said medium to circulate through said chamber. 90
8. The combination with an insulator having a chamber therein, of a conduit having one end thereof connected with said chamber, an electrical heating element associated with said conduit for heating a circulating medium in said conduit to cause said medium to carry heat to said insulator by the circulation 95
9. The combination with an insulator having a chamber therein, of a conduit having one end thereof connected with said chamber, an electrical heating element associated with said conduit for heating a circulating medium in said conduit to cause said medium to carry heat to said insulator by the circulation 100
10. The combination with an insulator having a chamber therein, of a conduit having one end thereof connected with said chamber, an electrical heating element associated with said conduit for heating a circulating medium in said conduit to cause said medium to carry heat to said insulator by the circulation 105
11. The combination with an insulator having a chamber therein, of a conduit having one end thereof connected with said chamber, an electrical heating element associated with said conduit for heating a circulating medium in said conduit to cause said medium to carry heat to said insulator by the circulation 110
12. The combination with an insulator having a chamber therein, of a conduit having one end thereof connected with said chamber, an electrical heating element associated with said conduit for heating a circulating medium in said conduit to cause said medium to carry heat to said insulator by the circulation 115
13. The combination with an insulator having a chamber therein, of a conduit having one end thereof connected with said chamber, an electrical heating element associated with said conduit for heating a circulating medium in said conduit to cause said medium to carry heat to said insulator by the circulation 120
14. The combination with an insulator having a chamber therein, of a conduit having one end thereof connected with said chamber, an electrical heating element associated with said conduit for heating a circulating medium in said conduit to cause said medium to carry heat to said insulator by the circulation 125
15. The combination with an insulator having a chamber therein, of a conduit having one end thereof connected with said chamber, an electrical heating element associated with said conduit for heating a circulating medium in said conduit to cause said medium to carry heat to said insulator by the circulation 130

- of said medium, and means for energizing said heating element.
9. The combination with an insulator having a chamber for circulating a medium, of a pump for circulating a medium through said chamber, and means for heating said medium.
10. The combination with an insulator having a chamber therein, of a circulating fluid disposed in said chamber, an expansion chamber or reservoir communicating with said chamber, and means for heating the fluid in said chamber and for producing circulation thereof.
11. The combination with a transmission line, of an insulator for supporting said line, said insulator having a chamber therein, a heating medium disposed in said chamber, and means energized by said transmission line for heating the medium in said chamber.
12. The combination with a transmission line, of an insulator for supporting said line, said insulator having a chamber therein for receiving a heating medium, and a flexible conduit connected with the upper portion of said insulator for supplying a heating medium to said chamber.
13. The combination with a transmission line, of an insulator for supporting said line having a chamber therein for a heating medium, and a pair of flexible conduits connected with the upper portion of said insulator for supplying a heating medium to said chamber and for circulating said medium.
14. The combination with a transmission line, of an insulator for supporting said line having a chamber therein, a pair of flexible conduits connected with the upper portion of said insulator, a tube connected with one of said conduits within said chamber and extending to the bottom portion of said chamber, and means for heating the conduit connected with the tube in the chamber and for causing an inflow of a medium through said conduit and tube.
15. The combination with a transmission line, of an insulator for supporting said line having a chamber therein, a conduit having one end thereof connected with the upper portion of said chamber and the other end connected with the lower portion of said chamber, a heating medium filling said chamber and conduit, and means energized from said transmission line for heating the medium in said conduit.
16. The combination with an insulator for supporting a conductor, of means for supplying heat to said insulator from a distant source to raise the temperature of the surface of said insulator above that of the surrounding atmosphere.
17. The combination with an insulator, of means spaced from said insulator for generating heat, and means for directing the heat so generated to said insulator to raise the temperature of the surface of said insulator above that of the surrounding atmosphere.
18. The combination with an insulator having a circulation duct therein, of means for circulating a heating medium through said duct to raise the temperature of the surface of said insulator above that of the surrounding atmosphere.
- In testimony whereof I have signed my name to this specification this 11th day of December, A. D. 1929.
- ARTHUR O. AUSTIN.
